J. C. DEAGAN.

HAMMER,

APPLICATION FILED JUNE 6, 1917.

1,291,777.

Patented Jan. 21, 1919.

UNITED STATES PATENT OFFICE.

JEFFERSON CLAUDE DEAGAN, OF CHICAGO, ILLINOIS.

HAMMER.

1,291,777.

Specification of Letters Patent.

Patented Jan. 21, 1919.

Original application filed November 13, 1916, Serial No. 130,979. Patent No. 1,233,989, dated July 17, 1917.
Divided and this application filed June 6, 1917. Serial No. 173,116.

To all whom it may concern:

Be it known that I, JEFFERSON CLAUDE DEAGAN, citizen of the United States, residing at Chicago, in the county of Cook and State of Illinois, have invented a certain new and useful Improvement in Hammers, of which the following is a full, clear, concise, and exact description.

This application is a division of my application 130,979, filed November 13, 1916, and upon which application there have been issued Letters Patent No. 1,233,989, dated July 17, 1917.

The invention relates to hammers and includes a hammer head and means for adjusting the hammer head whereby different parts of the head may be selected to strike with. These different striking parts of the hammer head are of differing striking effectiveness and may be selectively employed for striking. In one embodiment of the invention these different parts of the hammer head are either of differing degrees of hardness or elasticity or are at unequal distances from the axis of the hammer stem or have both of these characteristics.

The hammer head is rotatably mounted upon the hammer stem and is provided with means whereby it may be held in different positions of rotary adjustment.

I will explain my invention more fully by reference to the accompanying drawing showing the preferred embodiment thereof as embodied in an electric hammer action for a musical instrument. In the drawing Figure 1 illustrates an electric hammer action, the structure being illustrated partially in section and partially in elevation, the circuit of the action being diagrammatically illustrated; Fig. 2 is a side view of the structure shown in Fig. 1 with the hammer head in an alternative adjustment; Fig. 3 is a perspective view showing the manner in which the hammer head may be rotatably adjusted upon its stem; and Fig. 4 is a longitudinal sectional view taken through the hammer head co-incident with the axis of the stem, parts being shown in full elevation.

Like parts are indicated by similar characters of reference throughout the different figures.

The sound producing element illustrated is in the form of a vibrant bar 1 located in front of a resonator 2. The hammer action

includes an electro-magnet 3 whose armature 55 carries switching mechanism at 4 for automatically breaking the electric circuit after its establishment by the playing key 5 and after the hammer head has struck the bar, as will be well understood by those skilled in the art, and as the circuit arrangement forms no part of my present invention a detail description thereof will not be required. The hammer action illustrated includes a stem 6 for the hammer head, this stem being 65 carried by the armature 7 or other hammer head actuator. The stem 6 carries a flange 8 that is fixed thereupon, this flange carrying fingers 9 extending parallel to or longitudinally of the stem, these fingers being on 70 diametrically opposite sides of and substantially equidistant from the stem. The fingers are receivable in holes 10 that may be brought into register therewith and which holes are provided in the harder and larger 75 part of the hammer head 11 that is preferably made of ebony or other hard wood. These holes are also on diametrically opposite sides of and equidistant from the stem, the distance of these holes from the stem 80 being the same as that of the fingers from the stem. The outer or free end of the stem is threaded and receives a nut 12 constituting an adjustable abutment for a coil spring 13 surrounding the stem and which is interposed between the abutment nut 12 and the hammer head portion 11. The portion 11 of the hammer head is movable longitudinally of the stem 6 and, when free of engagement with the fingers 9, is rotatable upon such 90 stem. When the hammer head is moved outwardly against the force of the spring 13 it may be turned a half revolution to bring the openings 10 into new alignment with the hammer head for presenting a new striking surface to the sounding bar, the spring 13 maintaining the hammer head in fixed engagement with the stem by pressing the hammer head against the flange 8 and maintaining the engagement between the fingers 9 and the openings 10. The hammer head has two striking sides that are diametrically opposite. The striking side 14 is hard, being in one piece with the major part 11 of the wooden hammer head. The striking side of 105 the hammer head diametrically opposite to the striking side 14 is desirably made of a softer material such as a rubber button 15

held in place by a nail 16 that is driven into the wooden part of the hammer head. By the structure illustrated and described either striking part 14 or 15 of the hammer head 5 may be brought into striking relation to the sound producing bar 1 and, in the preferred embodiment, the relatively hard and soft striking parts of the hammer head are at differing distances from the hammer stem or 10 axis of rotation of the hammer head, the soft side 15 of the hammer head being desirably slightly closer to the axis of rotation of the hammer head than the hard side 14. The side 15 of the hammer head thus serves to 15 produce softer tones from the vibrant bar not only by reason of the softer material of which it is made but also because it is not quite within the same close range of the vibrant bar as may be occupied by the harder 20 striking side 14 of the hammer head, though the invention is not to be thus limited. In 25 Fig. 1 the soft side 15 of the hammer head is shown in striking relation to the vibrant bar 1 whereas in Fig. 2 the hard side 14 of the hammer head is shown in striking rela-

tion to the vibrant bar and slightly nearer thereto.

I claim:

A hammer including a stem; a flange upon the stem; fingers upon the flange and extending longitudinally of the stem, these fingers being on diametrically opposite sides of and substantially equidistant from the stem; a hammer head rotatable upon the stem and movable longitudinally thereof, 30 said hammer head having holes on diametrically opposite sides of said stem and equidistant therefrom, the distance of these holes from the stem being the same as that of the fingers from the stem; an abutment on the 35 outer end of the stem; and a coil spring surrounding the stem and which is interposed between said abutment and the hammer head, said hammer head having two diametrically opposite striking sides of differing 40 effectiveness.

In witness whereof, I hereunto subscribe my name this twelfth day of May A. D., 1917.

JEFFERSON CLAUDE DEAGAN.
